UNITED STATES PATENT OFFICE.

GEORGE M. FRENCH, OF CHICAGO, ILLINOIS, ASSIGNOR TO ECONOMY ENGINEERING COMPANY, OF CHICAGO, ILLINOIS, A CORPORATION OF ILLINOIS.

PORTABLE TIERING MACHINE.

Application filed December 22, 1919. Serial No. 346,666.

To all whom it may concern:

Be it known that I, GEORGE M. FRENCH, a citizen of the United States, residing at Chicago, in the county of Cook and State of Illinois, have invented certain new and useful improvements in Portable Tiering Machines, of which the following is a specification.

The invention relates in general to a machine for raising and lowering heavy objects, such as boxes, bales and the like, and has especial reference to a machine for facilitating the handling of bales of cotton so as to facilitate the stacking of the bales one upon another in warehouses, or freight cars, or upon wharves and similar platforms.

One object of the invention is to provide a tiering machine of a practical construction in which the parts are compactly arranged and are operable within a space not exceeding the floor space occupied by the machine.

Another object of the invention is to provide a tiering machine of an advantageous character in which the load-carrying platform is capable of being elevated to a position from which the load may be removed in any one of three directions.

A further object of the invention is to provide improved means for effecting the elevation of the load-carrying platform.

A further object of the invention is to provide means of advantageous construction for controlling the descent of the platform.

In the drawings, Figure 1 is a side elevation of the preferred embodiment of my tiering machine. Fig. 2 is another view in side elevation, but showing the load carrying platform in raised position. Fig. 3 is a vertical fragmental sectional view taken on line 3-3 of Fig. 1. Fig. 4 is a central sectional view slightly enlarged, of one of the dash-pots employed to guide and cushion the load-carrying platform. Fig. 5 is a section taken on line 5-5 of Fig. 4. Fig. 6 is a view, partly in section, of the clutch mechanism employed in the machine.

Briefly, the machine comprises a framework 1 mounted on wheels 2 and having a drawing handle 3. A load-carrying platform 4 is adapted to be swung and at the same time moved bodily upwardly from the position shown in Fig. 1 to that shown in Fig. 2. 5 designates, generally, the actuating mechanism for the platform.

The framework 1 is preferably composed of angle bars suitably secured together and herein it has two supporting legs 1^a. A base portion 6 carries said wheels, and rising from the base and secured thereto on opposite sides of the framework are two uprights 7. Midway of the length of the base are secured two upright channel-bars 8, and at the extreme rear end of said base are two upright angle bars 9. The members 8 and 9 are inclined toward each other and at their upper ends are secured together by gusset plates 10. These members, together with the base 6, thus constitute triangular frames of substantial strength and rigidity. Each of the plates 10 has secured thereto one end of a brace bar 11 the other end of which is secured by means of a bracket 12 to an upright 7, while horizontal cross bars 13 and 14 between the channel bars 8 further serve to strengthen the framework of the machine.

The load-carrying platform 4 herein consists of a pair of spaced longitudinal members 15. Said members are suitably connected at their lower ends and have an outwardly projecting toe 17 for insertion under the article to be lifted. On each of the members 15 are secured in spaced relation plates 19 and 20 to which are rigidly secured arms 21 and 22. Said arms are inclined toward each other and at their intersection are secured together to form a frame or bracket. Brackets are thus provided on opposite sides of the platform, and they carry at their apexes rollers 23 which are adapted to operate in the channel irons 8, as best seen in Fig. 3. To the upper end of the platform 4 links 24 are pivotally secured at 25, the other end of said links being pivotally secured at 26 to the uprights 7. Said links act to guide the front end of the platform when it is being raised or lowered.

I preferably employ manually operable means for raising and lowering the load-carrying platform 4, although it will be understood that means of any other preferred form may be employed for this purpose. Referring to Figs. 1 and 2, this mechanism comprises a winding sheave 27 fixed upon a shaft 28 and having one end of a cable 29 secured thereto and extending upwardly over a guide pulley 30 and then downwardly for connection at its opposite end with the plat-

form. The shaft 28 which carries the sheave 27 extends longitudinally of the machine, being journaled at one end in the crossbar 14 and at its other end in a frame 31. This frame is also adapted to provide means for mounting mechanism for actuating the shaft 28 and controlling the movements thereof as will hereinafter more fully appear. The guide pulley 30 is preferably 10 mounted to swing on a vertical axis, and for this purpose is supported in a pivoted frame 32 mounted between the crossbar 13 in the framework and a top crossbar 33 connecting the bars 11 of the framework. The lower 15 end of the cable 29 is secured to a crossbar 34 (Fig. 3) connecting the lower ends of the upright supporting arms 22 of the platform 4.

Within the frame 31 at the forward end 20 of the machine is located the actuating mechanism for the raising and lowering means. This mechanism comprises a gear wheel 35 fixed upon the shaft 28 and meshing with a pinion 36 rigid with a shaft 37 25 carried by the frame. The shaft 37 has also fixed thereon a gear wheel 38 which meshes with a pinion 39 which is arranged to be operable by means of a hand crank 40. Between the pinion 39 and the hand crank 30 40 I preferably provide clutch mechanism of a well known construction by means of which the load-carrying platform may be maintained in its elevated position and, when desired, readily released for movement to 35 its lowermost position. Referring to Fig. 6, this clutch mechanism comprises generally a sleeve 41 with which the pinion 39 is rigid, said sleeve also having rigid therewith a friction drum 42. Said sleeve and 40 associated parts are mounted upon a shaft 43 suitably journaled in the frame, the rear end of the shaft being journaled in a bearing 44. The crank 40 is made rigid with a traveling sleeve 45 having a screw-threaded 45 connection with the shaft 43. Rotatably and slidably mounted on the shaft 43 adjacent the friction drum 42, is a ratchet wheel 46, and operatively associated with said ratchet wheel is a pawl 47 carried by the frame. On 50 the shaft 43 is fixed a thrust collar 48, and the rotation of the crank 40 in the direction to wind the drum is adapted to effect a movement of the clutch sleeve 41 into operative engagement with the thrust collar 55 whereby to lock the sleeve and associated parts upon the shaft 43.

It will be seen that by operating the 60 crank 40, the winding sheave 27 may be caused to rotate in a direction to elevate the load-carrying platform. In this operation the platform is guided by the channel bars 8 bodily upwardly and slightly rearwardly, and at the same time is swung about the rollers 23 as an axis from its lower or normal position with the platform inclined up-

wardly and forwardly (Fig. 1) to a horizontal position above the framework (Fig. 2). Such swinging movement of the platform, it will be noted, is effected by the links 24 as the platform is guided in its movements 70 by the channel bars 8. The result of this compound movement of the platform is that the platform is not only swung from an upright to a horizontal position, but is also elevated bodily to a substantial height clear of 75 the machine so that the bale of cotton or other object upon the platform may be moved laterally from off the platform in either of three directions. Moreover, it will be seen that in its movements the load-carrying platform does not require any greater space than the floor space occupied by the machine, the platform being caused by the links 24 to move forwardly while it is moving upwardly as guided by the channels 85 8.

The clutch mechanism is arranged to be actuated by the operation of the crank 40 to prevent a reverse rotation of the sheave 41, and thus hold the platform 4 in its elevated 90 position. Referring again to Fig. 6, this is effected by the action of the pawl 47 engaging the ratchet wheel 46 as the platform, by reason of its tendency to descend, exerts a pull on the cable 29 causing the pinion 39 95 on the clutch shaft 43 to reversely rotate, and through its associated parts to rotate the clutch shaft so as to cause it to move forwardly into the sleeve 45. In this movement the friction drum 42 is forced tightly 100 into engagement with the ratchet wheel 46 which is held stationary by its pawl 47.

Means are provided for preventing a sudden lowering of the load-carrying platform. Herein this means comprises a pair of dashpots interposed between the framework and the load-carrying platform. These dashpots each comprise a cylinder 49 pivotally mounted upon the base 6 as at 50 on opposite sides of the machine. Within the cylinders (Fig. 110 4) are pistons 51 having rods 52 pivotally connected to the swinging links 24. Each of said pistons is provided with a plurality of ports 53 circumferentially arranged (Fig. 5) and normally closed by a spring-pressed 115 valve disk 54 on its under side. Said disk has an annular groove 55 therein registering with each of the ports 53 in the piston, and through the disk, leading from such groove is a port 56 of restricted diameter. It will 120 be seen that as the pistons move upwardly in the elevation of the frame, oil or other fluid contained in the upper portion of the cylinders will flow through the ports 53 in the pistons forcing the valve disks 54 downwardly against the action of their springs to permit the oil to flow at a comparatively rapid rate to the lower portion of the cylinders. When, however, the pistons descend, in the lowering movement of 130

the load-carrying platform, the oil in the lower portions of the cylinders must pass through the restricted ports 56 in the valve disks, so that a sudden downward movement 5 of the platform is prevented. In their upper portions the cylinders are preferably enlarged as at 57 to provide for displacement of the oil by the pistons as they descend into the lower ends of the cylinders.

10 The dashpots are arranged to coact with the clutch mechanism to effect a release of the clutch and permit the platform to descent. Such release of the clutch is effected by a reverse rotation of the crank 40 a number 15 of turns more rapidly than the clutch shaft is rotated by the weight of the platform acting through the cable 29 and pinion 39.

Such reverse rotation of the crank acting 20 through the sleeve 45 and associated parts effects longitudinal movement between the clutch sleeve 41 and the shaft 43, so that the thrust collar 48 moves rearwardly into frictional engagement with the bearing 44 25 on the frame. The friction drum 42 is now permitted to move, under the action of a spring 58 out of engagement with the ratchet wheel 46 and thus to freely rotate in the lowering movement of the platform. For a 30 more detailed description of the specific clutch mechanism herein set forth, reference is made to Patent No. 1,177,265 dated March 28, 1916.

Normally the machine is supported at its 35 forward end by the legs 1^a, and when it is desired to move the machine, these legs are lifted slightly from the floor or other supporting surface. Herein this is accomplished by mounting the forward supporting wheel 2 of the machine upon an angular bracket 59 mounted to swing on a horizontal axis as well as upon a vertical axis through the operation of the handle 3. The bracket 40 is so shaped and proportioned that when the 45 handle is in its upright position the machine rests upon the legs 1^a, but when the handle is moved downwardly the wheel 2 moves rearwardly and elevates the machine slightly from off its legs 1^a. Obviously when the 50 machine is supported upon the legs it is effectively held against accidental movement.

It will be seen that I have provided a 55 machine of rigid construction so that it is capable of handling heavy loads and withstanding severe usage. The peculiar movement which is imparted to the load-carrying platform renders the machine particularly advantageous in crowded warehouses and similar places where the operating space is 60 limited. At the same time it is possible to elevate a heavy bale of cotton or other object to a substantial height with comparative ease, in which position the load may be readily removed in the desired direction. An especially 65 advantageous feature of my ma-

chine is that resulting from the coacting effect of the clutch and dashpots in permitting the practically automatic descent of the load-carrying platform, the necessity of control by the operator being eliminated after 70 he effects a release of the platform through the reverse operation of the operating crank.

I claim as my invention:

1. A machine of the character described comprising, in combination, a load-carrying 75 platform, means for guiding the platform from a lower loading position to an elevated unloading position, means for elevating the platform including an operating crank and clutch mechanism adapted to hold the platform in raised position, and cushioning means for effecting a gradual descent of the platform, said clutch mechanism being releasable by a reverse rotation of the crank 80 while the weight of the platform is partially sustained by said cushioning means.

2. A device of the character described comprising, in combination, a base, a load-carrying platform having at its opposite sides a pair of supporting brackets, a pair 90 of upright guide members mounted on the base, rollers carried by said brackets and operable in said guide members, means for effecting a bodily upward movement of the platform, means for causing the platform to 95 swing about said rollers as an axis from an upright position when in its normal or lower position to a substantially horizontal position when elevated, and a dashpot interposed between the base and the platform to 100 cushion the descent of the latter.

3. A machine of the character described comprising, in combination, a framework including a base and an upright frame, a pair of upright guide members on opposite 105 sides of the base, a load-carrying platform having at opposite sides thereof a pair of supporting brackets having rollers thereon operable in said guide members on the frame, a pair of links connecting said upright frame and said load-carrying platform to guide it from a normal upright position to an elevated substantially horizontal position, means for effecting the upward movement of said load-carrying platform, and a 110 pair of dashpots interposed between the base and the platform on opposite sides thereof to cushion the descent of the platform.

4. In a machine of the character described, the combination of a base, a load 115 supporting and carrying platform movable with respect to said base from a lowered upright loading position to an elevated horizontal unloading position, elevating means for said platform, automatically operable 120 fluid controlled cushioning means for cushioning the descent thereof, and means for guiding and limiting the movement of said platform with respect to said base comprising 125 roller elements interposed between said 130

platform and the frame of said base and a link connecting said platform and the frame of said base.

5. A portable tiering machine comprising, in combination, a load-supporting platform, means for guiding the platform from a loading to an unloading position at different elevations, means for operating said platform including an operating crank, a clutch mechanism adapted for holding the platform in

elevated position, and means for cushioning the descent of the platform, said clutch mechanism being releasable by manipulation of said hand crank while the platform is partially sustained by said cushioning means. 15

In testimony whereof, I have hereunto set my hand.

GEORGE M. FRENCH.
